CLAIM

The ornamental design for a LED practice net, as shown and described.

DESCRIPTION

FIG. 1 is a front, top perspective view of a LED practice net, showing my new design;

FIG. 2 is a front elevational view thereof;

FIG. 3 is a rear elevational view thereof;

FIG. 4 is a left side view thereof, the right side view being a mirror image of FIG. 4;

FIG. 5 is a top plan view thereof;

FIG. 6 is a partial enlarged view of FIG. 1;

FIG. 7 is a partial enlarged view of FIG. 1;

FIG. 8 is a partial enlarged view of FIG. 2;

FIG. 9 is a partial enlarged view of FIG. 2;

FIG. 10 is a partial enlarged view of FIG. 3;

FIG. 11 is a partial enlarged view of FIG. 3;

FIG. 12 is a partial enlarged view of FIG. 4;

FIG. 13 is a partial enlarged view of FIG. 4; and,

FIG. 14 is a partial enlarged view of FIG. 5.

The dashed broken lines in the figures are for the purposes of illustrating portions of the LED practice net, which form no part of the claimed design.

The dash-dot-dash broken lines are for notating enlarged views, and form no part of the claim design.
